UNITED STATES PATENT OFFICE.

GEORGE WOODS, OF BOSTON, MASSACHUSETTS, ASSIGNOR TO MASON & HAMLIN, OF SAME PLACE.

IMPROVEMENT IN OPERATING SWELLS IN MUSICAL INSTRUMENTS.

Specification forming part of Letters Patent No. 36,756, dated October 21, 1852.

To all whom it may concern:

Be it known that I, GEORGE WOODS, of Boston, in the county of Suffolk and State of Massachusetts, have invented a new and Improved Mode of Opening the Swells of Melodeons, Harmonicons, &c.; and I do hereby declare that the following is a full and exact description thereof, reference being had to the accompanying drawings, and the letters of reference marked thereon.

The nature of my invention consists in attaching to the bellows or receiver an arm, which is so arranged as to act at the will of the performer upon the roller or lever, which in turn acts upon the swell or swells of the instrument, and this action is entirely effected by the exhaustion of the air from the bellows or receiver, which is governed by the performer through the pedals of the instrument, thereby obviating the necessity of removing the foot from the pedal to a side or independent pedal, which has hitherto been the case.

To enable others skilled in the art to make and use my invention, I will proceed to describe its construction and operation.

I attach to any part of the bellows or receiv-

er D, convenient for the purpose, an arm, A, Figs. 1, 2, 3, and 4. The arm E, Figs. 2 and 3, attached to the roller or lever B, communicates with the swell C, being placed under the end of the swell, which in turn is pressed downward by the spring G, Figs. 1, 2, 3, and 4. It will now be perceived that when the bellows or receiver D is closed, as in Fig. 1, this arm A is thrown up, elevating an arm of the roller or lever B, which opens, by being so elevated, the swell C, as shown in Fig. 1; but when the bellows or receiver D gradually returns, by the force of the spring F, Figs. 1, 3, and 4, to its original position, the swell becomes closed, as shown in Figs. 2, 3, and 4.

What I claim as my invention, and desire to secure by Letters Patent, is—

The operating of the swell or swells of melodeons, harmonicons, or other similar instruments, by the contraction and expansion of the bellows or any elastic receiver connected with the instrument.

GEORGE WOODS.
